UNITED STATES PATENT OFFICE.

HARVEY HUBLER, OF WEST SALEM, OHIO, ASSIGNOR OF ONE-HALF TO
E. L. PETERS, OF SAME PLACE.

PIPE-WRENCH WITH CUTTER.

SPECIFICATION forming part of Letters Patent No. 350,199, dated October 5, 1886.

Application filed May 15, 1886. Serial No. 202,246. (No model.)

To all whom it may concern:

Be it known that I, HARVEY HUBLER, a citizen of the United States, residing at West Salem, in the county of Wayne and State of Ohio, have invented a new and useful Improvement in Pipe Tongs and Cutters, of which the following is a specification.

My invention relates to an improvement in pipe tongs and cutters; and it consists in the peculiar construction and combination of devices, that will be more fully set forth herein-after, and particularly pointed out in the claims.

Figure 1 is an elevation of my invention, partly in section, when adapted for use as a pipe-cutter. Fig. 2 is a similar view of the same when adapted for use as pipe-tongs. Fig. 3 is a transverse section taken on the line *x-x* of Fig. 1. Fig. 4 is a detail view of the movable rod carrying the cutter, and Fig. 5 is a detail view of the key.

A represents the main portion or head of my improved device, in one side of which is pivoted a lever-arm, B, having at its inner end a cam, C.

D represents an endwise-moving rod, which is secured in a longitudinal slot made in the head A, and is provided at its inner end with an anti-friction roller, E, which bears against the face of the cam. As shown in Fig. 2, the outer end of the rod D is serrated or roughened, as at F.

G represents a bar which slides in an opening made in the opposite side of the head A, and which projects beyond the ends of the said head for a considerable distance. On the inner side of the bar G, at about the central portion thereof, is made a series of ratchet-teeth, *g*. The rear arm or end of the said bar forms a handle or lever, and the front end thereof is bent to form a semi-hexagonal engagging-arm, *g'*. The inner sides of the said arm are also serrated or roughened, as shown in Fig. 2.

H represents an oblique-moving key, which is inserted in an opening made in the head A, and is provided on its plane side with serrations or teeth *h*, adapted to engage the ratchet-teeth of the bar G. In one side of the said

key is made an inclined slot, *h'*. A set-screw, I, passes through one side of the head A, and the inner end of the said screw enters the slot *h'*, thereby securing the key in the head and permitting it to be moved back and forth in an oblique direction therein.

When thus constructed, the apparatus is adapted to be used as a pipe-tongs. The pipe (which is represented by a dotted circle) is secured within the inclined sides of the arm *g'* by extending the rod G forwardly for a suitable distance from the head A, and then drawing the said rod rearwardly and securing it to the said head by means of the key. The operator then grasps the rear arm of the bar G and also the lever-arm B with one hand and draws the said lever-arm toward the bar G, thus causing the rod D to be moved forwardly by the cam, and its serrated outer end to bear firmly against the inner side of the pipe, thus firmly holding the same, as will be very readily understood.

In Fig. 1 the device is shown as a pipe-cutter. In the inclined sides of the arm *g'* are pivoted anti-friction-rollers *a*, and in the outer end of the movable rod D is journaled a cutting-disk, *d*. The pipe to be cut is clamped between the said friction-rollers and the cutting-disk, and the apparatus is caused to rotate on the pipe, with the cutting-disk bearing firmly against the pipe until the latter is severed.

Having thus described my invention, I claim—

1. The combination of the head A, the endwise-moving rod G, provided with the ratchet-teeth *g* and the arm *g'*, the key H in the head, having the teeth *h* to engage the teeth *g*, and the diagonal slot or groove *h'*, the screw I in the head, entering the said slot or groove, the cam-lever pivoted to the head, and the endwise-moving rod D, having its inner end bearing against the cam, substantially as described.

2. The combination of the head A, the endwise-moving bar G, having the hook-arm *g'* and the rollers *a*, the pivoted cam-lever B, and the movable rod D, bearing against the cam and having the rotating cutting-disk at its

outer end, for the purpose set forth, substantially as described.

3. The combination of the head A, the end-wise moving bar G, having the friction-rollers 5 a, the cam-lever B, and the movable rod D, actuated by the cam-lever and having the cutting-disk d, as set forth.

In testimony that I claim the foregoing as my own I have hereto affixed my signature in presence of two witnesses.

HARVEY HUBLER.
